UNITED STATES PATENT OFFICE.

ALFRED H. WEISS, OF WILMETTE, ILLINOIS, ASSIGNOR TO KELLOGG SWITCHBOARD AND SUPPLY COMPANY, OF CHICAGO, ILLINOIS, A CORPORATION OF ILLINOIS.

SWITCHBOARD-PLUG.

1,401,217.

Specification of Letters Patent. Patented Dec. 27, 1921.

Application filed May 17, 1918. Serial No. 235,057.

To all whom it may concern:

Be it known that I, ALFRED H. WEISS, a citizen of the United States of America, and resident of Wilmette, in the county of Cook and State of Illinois, have invented certain new and useful Improvements in Switchboard-Plugs, of which the following is a specification.

My invention relates to improvements in plugs, and more particularly to switchboard plugs employed in telephone switchboards for connection purposes.

The usual form of switchboard plugs is provided with a main body portion, which body portion is provided with a protective sleeve of suitable insulating material and held against displacement or movement upon the body of the plug by means of a small screw which passes through the sleeve and screws into the body of the plug. This form of fastening necessitates the machining of parts as to drilling and tapping, thus adding to the cost of manufacture.

It is often necessary to change a damaged plug, or to change a damaged switchboard cord for another, and with the usual method employed the screw which holds the protective sleeve in place, being small, is apt to be lost. The screw is also hard to handle due to its smallness and requires considerable time to remove and replace the same, thereby making the repairing of switchboard plugs slow and tedious. Rapid repairs are essential in telephone switchboard work so as not to tie up any cord plugs for any length of time when making repairs. With the plug of my invention, all this amount of extra labor and time is eliminated.

An object of my invention is to construct a plug in which means is provided in the form of a split ring which rests in a groove in the forward end of the body portion of the plug to retain the protective sleeve in place on the body of the plug, thus doing away with the small screw which is almost universally used for holding the protective sleeve in place.

Referring now to the accompanying drawing, I illustrate several forms of my invention in which like reference characters in

the several views denote like parts, and in which—

Figure 1 is a view of the two-conductor plug assembled;

Fig. 2 is a sectional view of the plug taken 55 on the line 2—2 of Fig. 1;

Fig. 3 is a sectional view of the plug, similar to Fig. 2, but showing a modified form of my invention;

Fig. 4 is a sectional view of a plug similar 60 to Fig. 2, but showing still another modification of my invention; and

Figs. 5, 6 and 7 are views of different forms of split rings which may be used.

Referring now more in detail to my invention as illustrated and more particularly to Figs. 1, 2 and 5, the plug comprises a hollow body portion 2 having an extension 3 extending from one end of the body portion 2. The extension or sleeve of the plug 3 has 70 an opening which extends the length of the said sleeve 3 and is of a size to receive the sleeve 4, which sleeve is of suitable insulating material. A stem 6 of a size to pass through the insulating sleeve 4 is provided, 75 the end of the said stem 6 being threaded to receive the plug tip 5 of the plug, which tip 5 engages the tip contact of the spring jack, and the sleeve 3 of the plug being adapted to engage the sleeve of the spring jack, as 80 is well understood. The stem 6 is provided with an enlarged portion 8 which is insulated from the body portion 2 by means of an insulated sleeve 9. This enlarged portion 8 of the stem 6 is provided with a 85 binding screw 10, which screw 10 has screw threaded engagement with a tapped hole in the said enlarged portion 8. The binding screw 10 is adapted to hold the tip conductor of the cord in electrical contact with 90 the tip stem 6. A ring of insulation 11 is passed between the sleeve portion 3 and the tip 5 to insulate one from the other. The body portion 2 has its wall partly cut away to form an aperture 12 so that the binding 95 screw 10 is accessible therethrough. Surrounding the body portion of the plug is a protective sleeve 13 of suitable insulating material, such as fiber or hard rubber, which is slipped over the body portion 2 of the 100

C. F. WELDON.
MECHANICAL INKING APPARATUS.

UNITED STATES PATENT OFFICE.

CHARLES F. WELDON, OF DELAVAN, WISCONSIN.

MECHANICAL INKING APPARATUS.

1,401,218.

Specification of Letters Patent. Patented Dec. 27, 1921.

Application filed May 26, 1921. Serial No. 472,661.

To all whom it may concern:

Be it known that I, CHARLES F. WELDON, a citizen of the United States, residing at Delavan, in the county of Walworth, State 5 of Wisconsin, have invented a new and useful Mechanical Inking Apparatus; and I do hereby declare the following to be a full, clear, and exact description of the invention, such as will enable others skilled in the art 10 to which it appertains to make and use the same.

The invention relates to automatic apparatus whereby the ink within the fountain of a printing press will be thoroughly agitated at all times and equalized in such a manner that it will be uniform in consistency, and uniformly distributed throughout said fountain, thereby insuring adhesion of the ink to the fountain roller uniformly.

20 A further object is to provide a transversely disposed shaft, disposed above the ink fountain, said shaft having longitudinally movable thereon a carriage, which carriage is provided with an ink agitator. Also to 25 provide the carriage with mechanism co-operating with oppositely arranged spiral grooves on the shaft, by means of which grooves the carriage and agitator are moved longitudinally on the shaft.

30 A further object is to provide tripping fingers disposed adjacent the ends of the transversely disposed shaft and co-operating with mechanism on the carriage for reversing the direction of movement of the carriage and agitator.

A further object is to provide means whereby the agitator will be differently positioned during its reciprocation.

With the above and other objects in view 40 the invention resides in the combination and arrangement of parts as hereinafter set forth, shown in the drawings, described and claimed, it being understood that changes in the precise embodiment of the invention may 45 be made within the scope of what is claimed without departing from the spirit of the invention.

In the drawings:—

Figure 1 is a top plan view of the ink 50 fountain, showing the inking apparatus applied thereto.

Fig. 2 is a side elevation of the ink fountain showing the ink stirring device therein, and the ink stirrer frame in raised position 55 in dotted lines.

Fig. 3 is a sectional view taken on line 3—3 of Fig. 1.

Fig. 4 is a detail perspective view of the stirrer.

Referring to the drawings, the numeral 1 60 designates the fountain of a printing press in which fountain is rotatably mounted a fountain roller 2, in such a manner that as it revolves ink from within the fountain will be taken up thereon and transmitted to 65 the printing mechanism in the usual manner. It has been found that ink within the fountain is not equally distributed and of uniform consistency, therefore to overcome this objection a stirrer 3 is provided, which 70 stirrer is slidably mounted on a carriage 4 which moves longitudinally on a feed screw 5 which is rotatably mounted in bearings 6 of the pivoted frame 7. Feed screw 5 is provided with a bevel gear 7, which gear 75 meshes with a bevel gear 8 operated in any suitable manner from the main drive mechanism from the printing press in such a manner as to constantly rotate in the direction of the arrow *a*. The carriage 4 has mounted 80 in bearings 9 a shaft 10, which shaft is preferably in parallel relation with the feed screw 5 and is adapted to be rocked as the carriage approaches the ends of the feed screw for actuating mechanism which will 85 reverse the direction of movement of the carriage and consequently reverse the stirring action of the stirrer 3. The shaft 10 at one end thereof is provided with an arm 11 having a lug 12 with which lug the finger 90 13 located adjacent one end of the feed shaft 5 engages when the carriage reaches that end of the feed screw 5. When the finger 13 engages the lug 12 the shaft 10 is rocked 95 in its bearings until the feed screw engaging finger 14 is forced into the feed groove 15 as shown in Fig. 1, and as the feed screw 5 rotates in the direction of the arrow *a*, the carriage 4 will move in the direction of the arrow *b*. When the finger 14 is in engagement with the feed groove 15, said finger is held in engagement with said groove by means of the spring 16 which cooperates with the pivoted bar 17, which is pivoted as at 18 to a disk 19 carried by the 105 shaft 10 and slidably mounted in a pivoted bearing collar 20 pivoted to the side of the carriage as at 21. The holding action is accomplished by the pivotal point 18 passing between the center of the shaft 10 and 110

the pivotal point 21 until the disk 19 is limited in its rotation by engagement of the finger 14 with the feed groove 15. When the carriage 4 reaches the other side of the feed screw 5 the tripping finger 22 which is carried by the shaft 5 will move into engagement with the lug 23 carried by the arm 24 which is secured to the shaft 10 and force said arm 24 upwardly thereby rocking the shaft 10 and moving the groove engaging finger 25 into engagement with the feed groove 26, which feed groove will as the feed screw 5 revolves cause the carriage to be reversed in its operation and moved to the other end of the fountain 1. The above operation is a continuous one, and it will be seen that the stirrer 3 will move from one end of the fountain 1 to the other in such a manner that the ink therein will be constantly stirred, hence the ink will be maintained at a uniform consistency and properly fed on the fountain roller 2. When feed finger 25 is in engagement with the feed groove 26, the spring 16 and the shaft 17 are in the positions shown in Fig. 2, thereby maintaining the finger 25 in close engagement with the groove and preventing displacement of the same.

The stirrer 3 is provided with rearwardly and outwardly extending curved deflecting members 27, which members during the reciprocation of the stirrer deflect the ink in the direction of the fountain roller 2 so that it will readily feed unto said roller immediately following the stirring operation. Extending rearwardly from the stirrer 3 is an integral arm 28, the rear end of which is provided with a slot 29 through which slot a screw 30 extends. It will be seen that by providing slot 29 that the stirrer 3 may be moved toward and away from the fountain roller 2. To accomplish the above a bar 31 is slidably mounted in bearings 32 in the upper side of the carriage 4, the forward end of which bar 31 is pivotally connected as at 33 to the arm 34 of the lever 35. Lever 35 has its arm 34 pivotally connected as at 36 to the stirrer 3 and its arm 37 pivotally connected at 38 to the arm 39 carried by the shaft 10. It will be seen that as the direction of movement of the carriage 4 is changed at the ends of the strokes that the stirrer will be positioned differently in relation to the fountain roller 2 thereby positioning the stirrer so that during its

reciprocation it will not move through the same part of the ink fountain 1 but will be differently positioned, thereby insuring uniform and thorough stirring of the ink throughout the fountain.

From the above it will be seen that an ink equalizer is provided which is simple in construction and one wherein the parts are reduced to a minimum.

The carriage 4 is provided with a plate 40 having a notch 41 therein in which notch the flange 42 of the pivoted frame 7 is received. Plate 40 forms means for guiding the carriage 4 in its reciprocation.

The invention having been set forth what is claimed as new and useful is:—

1. The combination with an ink fountain of a printing press having a fountain roller rotatably mounted therein, of an ink agitator disposed in said fountain, said agitator comprising a carriage, said carriage being longitudinally movable in both directions on an oppositely spiral grooved feed shaft, means carried by the carriage for coöperating with the opposite grooves for moving the carriage during the rotation of the feed screw, tripping fingers carried by the ends of the feed shaft and coöperating with mechanism carried by the carriage for reversing the direction of the movement of the carriage adjacent the ends of the feed screw, an agitating element carried by the carriage and slidably mounted thereon at right angles to the fountain roller, means carried by the carriage and actuated by the reversing mechanism for moving the agitating element toward or away from the fountain roller when it reaches the end of the feed screw and means for rotating said feed screw.

2. The combination with an ink fountain of a printing press having a fountain roller therein, of an agitator longitudinally movable through said ink fountain in parallel relation to the fountain roller, and means whereby during the reciprocation of the agitator, said agitator at the time of change of direction of movement will be differently positioned in relation to the fountain roller.

In testimony whereof I have signed my name to this specification in the presence of two subscribing witnesses.

CHARLES F. WELDON.
